UNITED STATES PATENT OFFICE.

ELLIS L. JONES, OF LONG ISLAND CITY, NEW YORK, ASSIGNOR TO SEALED CONTAINERS CORPORATION, OF NEW YORK, N. Y., A CORPORATION OF DELAWARE.

APPARATUS FOR CLOSING AND SEALING RECEPTACLES.

Application filed October 19, 1927. Serial No. 227,162.

This invention relates to apparatus for closing and sealing the end of a receptacle or container made of pliable material, such as paper paraffined, and preferably of truncated 5 conical shape having a closure in the larger end and especially intended for the dispensing of milk or other liquid, the open end of the receptacle being adapted to be closed by collapsing or pinching together the smaller end 10 of the receptacle and then securing and sealing the end in collapsed condition by a clamping strip, and it is the object of the invention to provide improved apparatus, particularly adapted for manual operation, to collapse the open end of the receptacle and then 15 secure and seal a member applied to the collapsed end, and to an improved manner of firmly securing and positively sealing said member to the collapsed receptacle end to prevent leakage of the contents of the receptacle 20 should the same be inverted.

In carrying out the invention there is provided a standard carrying a receptacle support to have axial movement in a vertical direction and held against rotative movement, said support having means to gauge the position of the receptacle thereon, and said standard also carrying clamping jaws in vertical spaced relation to the receptacle support, one 25 of said jaws being fixed and the other having movement relative to the fixed jaw in a direction transverse to the movement of the receptacle support. A pair of receptacle collapsing levers are movably mounted upon opposite sides of the receptacle support to have 30 movement in a direction toward a receptacle on the support to collapse the same away from each other to release a receptacle from between the levers and permit of removal of 35 the receptacle from the support. Means are provided to impart axial movement to the receptacle support to position the collapsed end of a receptacle with a securing and sealing member thereon, comprising a strip of pliable 40 metal bent to inverted V shape in cross section, between the clamping jaws, said means being operative during the initial movement thereof to actuate the receptacle collapsing 45 levers to move and retain said levers in receptacle collapsing position. Means are provided to actuate the clamping jaws for the collapsed receptacle end when the securing 50 and sealing member thereon has been positioned between said jaws. One of the jaws is 55 arranged with a longitudinal recess and the

other with a rib alined with said recess whereby as the jaws are brought together to clamp the securing and sealing member to the collapsed receptacle end it is arranged with a longitudinally fluted portion, said fluted portion not only reinforcing and adding rigidity to the member but draws the portion of the strip at the fold into firm and intimate engagement with the edge of the collapsed receptacle end. 60

To further assure the sealing of the securing strip to the receptacle portions of the strip at one side of the receptacle with the interposed material of the receptacle are offset into portions of the strip at the opposite sides 70 of the receptacle.

In the drawings accompanying and forming a part of this application Figure 1 is a side elevation, partly in section, of apparatus embodying the invention showing the parts 75 in normal position with a receptacle, shown in dot and dash line, on the receptacle support.

Figure 2 is a perspective view of the receptacle support.

Figure 3 is a perspective view of a receptacle collapsing lever. 80

Figure 4 is a view similar to Figure 1 on a reduced scale and certain of the parts removed, and showing the receptacle collapsing levers in receptacle collapsing position. 85

Figure 5 is a view similar to Figure 4 and showing the receptacle support adjusted to position with the collapsed receptacle end and a sealing member applied thereto between the clamping jaws. 90

Figure 6 is a side elevation of the upper portion of the apparatus shown in Figures 4 and 5, and showing the one clamping jaw as having been actuated to clamp the securing and sealing member to the collapsed receptacle end between the jaws. 95

Figure 7 is a plan view of the apparatus with portions broken away so that the parts below the same may be seen.

Figure 8 is a perspective view of the clamping jaws, one of the jaws being broken away and in section to show the mounting of offsetting punches therein. 100

Figures 9 and 10 are perspective views of means for connecting the operating means to the receptacle collapsing levers and receptacle support. 105

Figure 11 is a perspective view of the securing and sealing member for the collapsed receptacle end. 110

Figure 12 is a side elevation of the collapsed end of the receptacle showing a securing and sealing member applied thereto preparatory to positioning the same between the 5 clamping jaws; and

Figure 13 is a sectional view of the collapsed end of the receptacle secured and sealed in closed condition.

The embodiment of the invention illustrated in the drawings comprises a standard S extending upward from a base plate B which is arranged with perforations for the engagement of screws or bolts to secure the same to the support, such as a table or bench 10. The standard has a pair of laterally extending and vertically spaced projections 15, 16 extending from the front thereof. The projection 16 has a tubular portion 17 with a vertical bore therethrough for the slidable 15 engagement of a stem 18 of a receptacle support 19 in the form of a disk having a ledge 20 extending upward from the periphery for substantially one-half of the circumference and at one side to serve as a gauge for positioning a receptacle R thereon, shown in dot and dash lines. To prevent rotative movement of the receptacle support a pin 21 is extended transversely therethrough with the projecting ends extended through opposite 20 slots 22 in the wall of the tubular portion 17. Two pairs of perforated lugs 23 extend laterally and upwardly from the opposite sides of the support for the pivotal mounting of a pair of receptacle collapsing levers 24 to be 25 arranged at the front and rear of the support. One arm of each lever is elongated and extends upwardly to engage at opposite sides of the receptacle on the support with the free ends offset inwardly and extended laterally, 30 as shown at 25.

The upper projection 15 carries a pair of clamping jaws 26, 27, the jaw 27 being secured in a transverse recess of the projection by screws 28, while the jaw 26 is secured by 35 screws 29 in a transverse recess in a head 30 in opposed relation to the jaw 27, said head being fixed to the forward end of a slide in the form of a pair of rods 31 slidably mounted in the standard projection 16 and the rear 40 ends of the rods having a connector 32 secured thereon. (Figure 7). Plates 33 are secured to the opposite ends of the jaw 27 to extend forwardly and downwardly therefrom to serve as guides to position the collapsed end of a receptacle between the jaws. 45

Means are provided to actuate the receptacle collapsing levers to move them toward each other to collapse a receptacle on the receptacle support and away from each other 50 to release the collapsed receptacle and in timed sequence therewith actuate the receptacle support to position the receptacle end between the clamping jaws and from between said jaws. This means comprises a collar 33' 55 (Figure 9) having opposite laterally elongated

recesses 34 for the engagement of the ends of the pin 21 extended transversely through the support carrying stem, said collar having bifurcated portions 35 extending laterally therefrom at right angles to the recesses 34 70 and in which bifurcation one end of links 36 are pivotally supported, the opposite ends of which links are pivotally connected with the other arms of the levers 24, as at 37. The collar also has a pair of perforated lugs 38 extending downwardly in alined relation with the recesses 34 for the connection of the collar with one arm 39 of a rocker by means of an interposed link member 40, one end of which link member is pivotally supported in 75 a bifurcation 41 at the end of the rocker arm, and the opposite end having an elongated sleeve portion whereby it is pivotally supported between the collar lugs 38. By this arrangement of link connection of the collar with the rocker lateral distorting movement of the collar is prevented. The rocker is pivotally mounted at 42 on a lug 43 extending downwardly from the base B of the standard 80 and is actuated by a pair of cams 44, 45 arranged on a disk fixed to and movable with a manually operative lever 46 and also pivotally mounted on the lug 43 and co-operating with cam faces 47, 48 arranged on an arm 49 of the rocker extending oppositely to the 85 arm 39.

In the operation of the apparatus a receptacle R is engaged upon the receptacle support 19 from the side when viewed from the front of the standard and positioned on the 90 support by the gauge ledge 20 when the lever 40 is pulled downward. During the initial movement of the lever the cam 44 is brought into engagement with the cam face 47 on the rocker arm 49 imparting a lost motion to 105 the collar 33, that is, without imparting movement to the receptacle support. This movement of the collar rocks the collapsing levers moving them into engagement with and collapsing the receptacle end, as shown 110 in Figure 4. By the continued movement of the lever the cam 45 is brought into engagement with the cam face 48 on the rocker arm 49 thereby moving the receptacle support to position the collapsed receptacle end between the 115 clamping jaws, as shown in Figure 5, through the collar 33' and its connection with the receptacle support through the links 36 connected with the collapsing levers, this force also applying a pressure to the collapsing levers to 120 maintain the receptacle in firm collapsed condition. The engagement of the collapsed receptacle end with the sealing member thereon between the clamping jaws is limited by the inwardly extending portions 25 of the collapsing levers engaging with the guiding and positioning members 33 connected to the ends of the clamp 27. In the interim of collapsing the receptacle and positioning it between the 125 clamping jaws the securing and sealing mem- 130

ber is applied to the collapsed receptacle end by engaging the same thereon, as shown in Figure 12. This member is indicated at 50 in Figure 11 and comprises a strip of pliable metal bent longitudinally upon itself to V shape in cross section with the fold or bend of the strip having a relatively small radius and preferably transversely serrated to reinforce the same. With the collapsed receptacle end positioned between the clamping jaws as shown in Figure 5 the clamp member carrying head 30 is actuated to move it toward the clamping jaw 27 to clamp the securing and sealing strip 50 to the receptacle end. This movement is imparted to the jaw carrying head 30 by a manually operative lever 51 pivotally mounted at 52 on the standard and having a counterweight adjustably mounted on an arm extending oppositely to the lever, as at 53. The operating lever has a toggle link connection with the jaw head carrying rods 31 comprising a link 54 pivotally mounted at one end in a recess in the standard projection 15, as at 55, and a link 56 pivotally connected at one end to the rod connecting head 32, as at 57, the opposite end of the link engaging in a bifurcation 58 of the link 54 and mounted with the bifurcated end of the link 54 upon a pin 59 with the connecting pin 59 connected with the operating lever by a pair of links 60 hung on the ends of a pin 61 extended transversely through the operating lever and engaged upon the ends of the pin 59 thereby connecting the links 54, 56. By a downward movement of the operating lever 51 the links 54, 56 will be straightened out but as the one end of the link 54 is mounted at 55 in fixed position in the standard and the one end of the link 56 is connected at 57 with the rod connecting head 32 said straightening of the links will impart movement to the jaw carrying head 30 toward the jaw 27. To limit and gauge the movement of the clamp jaw 26 relative to the clamp jaw 27 the movement of the toggle links 54, 56 is controlled by an adjustable abutment in the form of a screw 62 threaded into a rib 63 extending transversely of and below a recess 64 in the standard projection 15, and in which recess the toggle mechanism is arranged to operate. When the lever 51 is released the counterweight operates to return the jaw carrying head 30 to the Figure 1 position. The cam 45 of lever 46 and cam face 48 of rocker arm 49 are arranged so that the engagement of said parts will retain the receptacle supporting parts in the Figure 5 position, and when the clamping jaws are released the lever 46 is manually operated to release the rocker carrying the receptacle supporting parts connected thereto and permitting the parts to return to initial position by the weight thereof.

65 The face of the clamping jaw 26 is arranged with a projecting rib 65 of V shape in cross section extending longitudinally and intermediate the top and bottom of the clamp jaw, and the clamp jaw 27 is arranged with a longitudinal recess 66 of circulation shape in cross section and of a width and depth to correspond with the width of the base of the rib 65, as clearly shown in Figure 8. By the arrangement of the rib and recess in the clamp jaws as the sealing strip is clamped to the receptacle end the strip with the interposed material of the receptacle is longitudinally fluted, as shown at 67 in Figure 13, said fluting not only reinforcing and adding rigidity to the sealing member but also draws the strip onto the end of the receptacle so that the connecting portion of the sealing member is brought into firm and intimate engagement with the edge of the end of the receptacle, this close engagement of the sealing member with the edge of the receptacle end being facilitated by the bending of the strip on a small radius. To prevent longitudinal displacement of the sealing member on the receptacle and also assuring a further sealing of said member to the receptacle portions of the sealing member at one side of the receptacle are offset into the interposed material of the receptacle and the opposite side of the strip, as shown at 67 in Figure 13. This is effected by prick punches 68 mounted in and projecting from the face of the clamp jaw 27 and being in line with recesses 69 in the face of the clamp jaw 26. These punches and recesses are preferably arranged in the clamp jaws between the tops thereof and the rib 65 and recess 66. The clamping jaw 27 is arranged with a transverse recess or undercut portion 70 to compensate for the side sealing means to secure the blank at the longitudinal marginal edge portions of the blank in forming the receptacle body and thus assure an intimate engagement of securing and sealing member with the collapsed receptacle end.

75 It will be obvious that various modifications may be made in construction and arrangement of parts, and that portions of the invention may be used without others and come within the scope of the invention.

80 Having thus described my invention I claim:

1. In apparatus for closing and sealing the open end of a receptacle of pliable material, an axially movable receptacle support, clamping jaws arranged in opposed and spaced relation to the receptacle support and having movement one relative to the other in a direction transverse to the movement of the support, means carried by the receptacle support to have movement toward and away from a receptacle on the support to collapse the open end thereof, and means operative to actuate said receptacle collapsing means and move the receptacle support to position the

collapsed end of a receptacle on the support between the clamping jaws.

2. Apparatus for closing and sealing the open end of a receptacle as claimed in claim 1, wherein the means to collapse the open end of the receptacle comprises a pair of levers pivotally mounted on opposite sides of the receptacle support and extending upwardly therefrom with the free ends arranged with inwardly offset and laterally extending jaws for engagement with and collapsing of the receptacle.

3. Apparatus for closing and sealing the open end of a receptacle as claimed in claim 1, wherein the receptacle support embodies a disk arranged with a stem whereby it is mounted in the bore of a lateral projection of the framework and the disk stem having a pin extending transversely therethrough with the ends projected through opposite slots in the wall of the bore of the disk stem supporting projection.

4. Apparatus for closing and sealing the open end of a receptacle as claimed in claim 1, wherein the receptacle support embodies a disk arranged with a stem whereby it is mounted in the bore of a lateral projection of the framework and the disk stem having a pin extending transversely therethrough with the ends projected through opposite slots in the wall of the bore of the disk stem supporting projection and a lever actuated rocker arm having a connection with the pin extended transversely through the disk stem.

35 5. Apparatus for closing and sealing the open end of a receptacle as claimed in claim 1, wherein the receptacle support embodies a disk arranged with means for mounting the same in the framework of the apparatus to have axial movement and held against rotative movement, and a lever having connection with the disk to impart axial movement thereto.

45 6. In apparatus for closing and sealing the open end of a receptacle of pliable material, a standard having laterally extended and vertically spaced projections, a receptacle support mounted in the lower standard projection to have movement toward and away from the upper projection, clamping jaws mounted in the upper projection one to have movement relative to the other transversely of the movement of the receptacle support, levers pivotally mounted at opposite sides of the receptacle support and between which levers a receptacle is adapted to be engaged upon the support, one arm of the levers being extended upward and said arms adapted to have movement toward and away from each other to collapse the open end of a receptacle on the support, means to actuate the levers to impart receptacle collapsing movement thereto and in said position of the levers move the support to position the collapsed receptacle and between the jaws, and means to actuate

the clamping jaws to secure a sealing member applied to the collapsed receptacle end.

7. Apparatus for closing and sealing the open end of a receptacle as claimed in claim 6, wherein the receptacle support embodies a disk portion arranged with a gauge for positioning a receptacle thereon and having oppositely extending perforated ears by which the receptacle collapsing levers are supported.

75 8. Apparatus for closing and sealing the open end of a receptacle as claimed in claim 6, wherein the means to actuate the receptacle collapsing levers and receptacle support comprises a lever actuated rocker arm, and a collar connected with the rocker arm, the receptacle collapsing levers and the receptacle support.

80 9. Apparatus for closing and sealing the open end of a receptacle as claimed in claim 6, wherein the means to actuate the receptacle collapsing levers and receptacle support comprises a collar having a lost motion connection with the receptacle support, link connections between said collar and receptacle collapsing levers, and a lever actuated rocker arm operatively connected with the collar in line with the axis of the receptacle support.

95 10. Apparatus for closing and sealing the open end of a receptacle as claimed in claim 6, wherein the means to actuate the receptacle collapsing levers and receptacle support comprises a collar having a lost motion connection with the receptacle support, link connections between said collar and receptacle collapsing levers, a pivoted lever, a disk arranged with a pair of cams movable with the lever, and a rocker arm arranged with portions for engagement of said cams connected 100 with the collar.

11. Apparatus for closing and sealing the open end of a receptacle as claimed in claim 6, wherein one of the clamping jaws is fixed to the upper standard projection and the other clamping jaw is carried by a head fixed on a slide mounted in said standard projection.

110 12. Apparatus for closing and sealing the open end of a receptacle as claimed in claim 6, wherein one of the clamping jaws is fixed to the upper standard projection and the other clamping jaw is carried by a slide mounted in said standard projection, and gauge members at the ends of the clamping 115 jaws to guide and position the collapsed receptacle end between the jaws.

125 13. Apparatus for closing and sealing the open end of a receptacle as claimed in claim 6, wherein one of the clamping jaws is fixed to the upper standard projection and the other clamping jaw is carried by a slide mounted in said standard projection, and a lever pivotally mounted upon the standard 130 and having an operative connection with the

jaw carrying slide to move the jaw carried thereby in predetermined position toward and away from the fixed jaw.

14. Apparatus for closing and sealing the open end of a receptacle as claimed in claim 6, wherein one of the clamping jaws is fixed to the upper standard projection and the other clamping jaw is carried by a slide mounted in said standard projection, a lever pivoted on the standard, and a toggle link connection between the lever and jaw carrying slide.

15. Apparatus for closing and sealing the open end of a receptacle as claimed in claim 6, wherein the one clamping jaw is arranged with a longitudinal recess and the other jaw is arranged with a longitudinal rib operative to longitudinally flute the sealing member as it is clamped to the collapsed receptacle end.

20 16. Apparatus for closing and sealing the open end of a receptacle as claimed in claim 6, wherein the one clamping jaw is arranged with a longitudinal recess and the other jaw

is arranged with a longitudinal rib operative to longitudinally flute the sealing member as 25 it is clamped to the collapsed receptacle end, punches mounted in one jaw to project from the face thereof, and recesses in the face of the other jaw in line with said punches.

17. Apparatus for closing and sealing the open end of a receptacle as claimed in claim 6, wherein the one clamping jaw is arranged with a longitudinal recess and the other jaw is arranged with a longitudinal rib operative to longitudinally flute the sealing member as 30 it is clamped to the collapsed receptacle end, punches mounted in one jaw to project from the face thereof, and recesses in the face of the other jaw in line with said punches, said 35 punches and recesses being arranged in the clamping jaws above the longitudinal recess and rib.

Signed at the city of New York, in the county of New York and State of New York, this 6th day of Oct., 1927.

ELLIS L. JONES.
